UNITED STATES PATENT OFFICE.

DARIUS W. BUNKER, OF QUINCY, MASSACHUSETTS, ASSIGNOR TO UNITED SHOE MACHINERY CORPORATION, OF PATERSON, NEW JERSEY, A CORPORATION OF NEW JERSEY.

SAFETY DEVICE.

Application filed December 4, 1922. Serial No. 604,833.

To all whom it may concern:

Be it known that I, DARIUS W. BUNKER, a citizen of the United States, residing at Quincy, in the county of Norfolk and State 5 of Massachusetts, have invented certain Improvements in Safety Devices, of which the following description, in connection with the accompanying drawings, is a specification, like reference characters on the drawings 10 indicating like parts in the several figures.

This invention relates to safety devices and is herein illustrated as embodied in a guard and work supporting table designed 15 for use with a leather splitting machine.

A leather splitting machine commonly comprises a knife to which the pieces of leather are fed by a pair of feed rolls, and a table upon which the pieces are placed 20 one by one and over which they are pushed by the operator to present them to the feed rolls. The pieces of leather which are to be split vary greatly in length and in thickness; but, for the purpose of explaining 25 the present invention, top lifts and soles will be considered as representing the extreme limits. Top lifts are commonly not more than three inches in length and a quarter of an inch in thickness while soles are often several times that length and twice 30 that thickness. It should be understood that these figures are not intended to be accurate and are used merely to make clear a problem which is encountered when an attempt is 35 made to prevent injury to the fingers of the operator and at the same time to interfere in no way with the operation of the machine.

When top lifts are being operated upon, 40 any guard which is used should be fairly close to the feed rolls so that the short lifts may be presented to the bite of the rolls; it should also be as close as possible to the upper surface of the table so as to prevent 45 the operator from sticking the tips of his fingers through the opening between the guard and the table through which the lifts are presented. When soles are to be operated upon, the opening between the guard 50 and the table should be increased; but this increased space will permit the operator's fingers to pass through it with the consequent danger of being caught between the feed

rolls; and if, instead of increasing the space between the guard and the table, the guard 55 is merely moved farther away from the rolls, a thick sole cannot be presented to the machine.

In prior application Serial No. 275,846, filed in the name of myself and Charles M. 60 Bradford, a guard is disclosed which provides for the conditions stated above. This guard is capable of being adjusted into two positions, according to whether the pieces of stock are comparatively short and thin or 65 comparatively long and thick. When in position for use with top lifts or similar short pieces, it is located near the rolls of the splitting mechanism and with its lower edge spaced above the table just enough to 70 permit top lifts to be pushed beneath said edge. When in position for use with soles it is located at a distance from the rolls greater than the length of an operator's fingers and its lower edge is spaced from the table suf- 75 ficiently to permit soles to pass beneath said edge. In that machine the work table is made in one piece and is comparatively long. This is satisfactory when soles are being presented beneath the guard, which is then 80 at a considerable distance from the rolls, but necessitates objectionable reaching by the operator when top lifts are being presented and the guard is close to the rolls.

According to one feature of the present 85 invention, a work table is provided having a main section of a length suitable for top lifts or other short pieces of work and an extension section which is held in inoperative position when the guard is in its 90 forward position close to the mechanism for operating upon the work but may be moved into operative position in which it forms an extension of the main table when the guard occupies its position more remote from 95 the operating mechanism. There is thus provided a long table for long pieces of work and a short table for shorter pieces. Any preferable movement of the guard from one of its positions to the other moves the extension section of the table from operative to inoperative position or vice versa according to the direction in which the guard is moved.

Another feature of the invention relates 105 to an improved mounting of the guard

whereby its movement from one position to another is facilitated.

These and other features of the invention including certain details of construction and combinations of parts will be described as embodied in an illustrative machine and pointed out in the appended claims.

Referring to the accompanying drawings, Figure 1 is a side view, partly in section and partly in elevation, of a leather splitting machine in which the present invention is embodied.

Fig. 2 is an elevation of the extension section of the table and the link upon which it is mounted, and

Fig. 3 is a fragmentary perspective.

The leather splitting machine chosen for illustration comprises a frame 3, upper and lower feed rolls 5 and 7, a knife 9 and a table 11. The table is pivoted at 13 to the frame of the machine and has a depending arm 111 through the lower end of which is threaded an adjusting screw 14, one end of the screw engaging the frame 3 so that by manipulating the screw the table may be adjusted angularly. This adjustment, however, is commonly a small one, the table remaining substantially horizontal at all times. The rolls are driven continuously in a direction to feed the work to the knife, and the bearings of the upper roll are adjustable vertically toward and from the lower roll to determine the thickness to which the work shall be split. The machine, as thus far described, is old and well known and has been chosen first because it represents generally a type in which presentation of the work is accompanied by some danger and second because a particular danger is involved in the presentation of work to leather splitting machines due to the different thicknesses of work which are commonly operated upon.

Before describing the improvement in detail a brief outline of its mode of operation will be given. A guard 21 in the form of a plate of a length equal to or a little greater than the length of the rolls and having a curved lower edge 121 is so mounted that it may be moved to and held in either the full line or the dotted line position. In the full line position the opening between its lower edge 121 and the upper surface of the table 11 is of sufficient height to permit a comparatively thick piece of work such as a sole to pass through it but is not of sufficient height to permit the operator to push his fingers through it far enough to reach the feed rolls. When the guard is used on a splitting machine, the height of this opening is about five-eighths of an inch and the distance from the guard to the rolls is about six inches. In the dotted line position the opening between the lower edge of the guard and the upper surface of the table 11 is of less height than in the full line position, be-

ing sufficient then to permit a comparatively thin piece of work such as a top lift to pass through it but insufficient to permit even the tips of the operator's fingers to be pushed through it.

With regard to the table of the machine, the member 11, which has been referred to above for convenience simply as the table, is in the present machine really one section of the table and is comparatively short so as to be suitable for use with top lifts. In order to render the table longer for use with soles, there is provided an extension section 311 which is pivoted about the axis 39 and is so connected with the guard 21 that it is swung up into the full line horizontal position when the guard is moved back to its full line position and is swung down into a vertical inoperative position when the guard is moved forward into its dotted line position. There is thus provided in effect a short table for top lifts and a longer table for soles.

Proceeding now to a description of the details of the mounting of the guard, the main section 11 of the table has fastened to its opposite sides two bars one of which is shown at 12 in which are formed guideways 15 which are counterparts of and register with each other. These guideways extend away from the rolls first in a substantially horizontal direction and then in an upward curve. Extending one into each of these guideways and adapted to travel therein are two alined pins, one of which is shown at 17, the pins being driven into or integral with lugs 19 formed at opposite ends of the guard 21. Extending from the lower part of the guard 21 are two lugs, one of which is shown at 23, and pivoted to these lugs upon alined pins, one of which is shown at 25, are the upper ends of two links, one of which is shown at 27, the links carrying fastened to their lower ends a rod 29 which extends across the machine from side to side below the level of the main section 11 of the table. An arm 31 is fast at its upper end to the rod 29 near the middle of said rod and has at its lower end a pin 33 arranged to travel in a slot 35 formed in a flange 211 which is integral with the arm 111 of the main section 11 of the table. The main portion of this slot is substantially vertical, but at its upper end the slot curves nearly 180 degrees and terminates in a seat in which the pin 33 rests to hold the guard 21 in the position shown in full lines. The rod 29 is connected with the main section 11 of the table by a link 37 which is pivoted at its upper end at 39 to this section and at its lower end to the rod 29 so that the rod may swing bodily about the pivot 39.

When the guard 21 is in the position shown in full lines, the opening between the lower edge 121 of the guard and the table

is sufficient to permit a thick piece of work, such as a sole, to pass through it but is at the same time insufficient to permit the operator to push his fingers through it far enough to touch the feed rolls. When now it is desired to present to the rolls comparatively short thin pieces of work such as top lifts, the link 31 is raised and its lower end pulled toward the operator to withdraw the pin 33 from its seat and permit it to travel down in the vertical portion of the slot 35. The operator then pushes the links 27 toward the rolls 5, 7 until the guard and connected parts occupy the positions shown in dotted lines. In this position the guard is quite close to the rolls and its lower edge is much nearer to the table than it was in the full line position, the opening between the lower edge of the guard and the table being insufficient to permit the ends of the operator's fingers to be pushed through it. There are thus two operative positions of the guard; one in which it is spaced considerably from the table and at the same time is located at a distance from the rolls greater than the length of the operator's fingers, and the other in which it is spaced much less from the table and located much nearer the rolls. It should be noted, too, that when the guard is pulled back from the dotted line position to the full line position the lower edge of the guard, owing to the direction of extent of the registering guideways 15, remains close to the table for a considerable distance and is not raised until it is so far from the rolls that the operator cannot possibly reach the rolls with his fingers by pushing them between the lower edge of the guard and the table.

40 The extension section 311 of the table is integral with the link 37 and so carried by the link that when the link occupies its full line position the upper surface of the extension section is in the same plane with 45 and forms an extension of the upper surface of the main section 11 of the table; and, when the link has swung to its dotted line position the extension section has swung down into a vertical position entirely out of the way of the operator. The construction and mounting of the guard and extension is, therefore, such that, when the guard is located away from the rolls and with its lower edge considerably spaced from the table, the extension is in its operative position and the table is a comparatively long one; and, when the guard is located near the rolls and with its lower edge closer to the table, the extension is swung down out of the way and the short main section 11 may be used without the extension.

With regard to the mounting of the guard it should be noted that, since the members 50 27 and 31 are fast to the rod 31, they form

in effect a single arm, and that this arm is connected to a stationary part of the machine by the link 37.

In order to ensure that an operator shall not be able to reach over the guard at any time and thereby risk catching his fingers between the feed rolls, a shield 41 is hinged at its rear end to the upper portion of the guard 21 and extends through the upper portion of the machine above the rolls. This shield rests upon lugs formed on the frame of the machine and slides back and forth with the guard.

Although the invention has been described in connection with a particular machine, it should be understood that the invention is not limited in the scope of its application to the particular machine which has been shown and described.

Having thus described my invention, what I claim as new and desire to secure by Letters Patent of the United States is:—

1. The combination with mechanism to which pieces of work are presented by an operator, of a table having a section adjacent the mechanism and an adjustable section movable into and out of operative position in which it forms an extension of the main section, and a guard adapted to be moved into and held in two positions, one near the mechanism and another more remote from the mechanism.

2. The combination with mechanism to which pieces of work are presented by an operator, of a table having a section adjacent the mechanism and an adjustable section movable into and out of operative position in which it forms an extension of the main section, and a guard adapted to be moved into and held in two positions, one near both the mechanism and the plane of the face of the table and another more remote from both the mechanism and the plane.

3. The combination with mechanism to which pieces of work are presented, of a table comprising a main section suitable for use with short pieces of work and an adjustable extension section adapted when in operative position to lengthen the main section when longer pieces of work are to be operated upon, a guard adjustable into one position for use with short pieces of work and into another position for use with longer pieces of work, and connections between the extension section and the guard such that the extension and the guard may be adjusted simultaneously.

4. The combination with mechanism to which pieces of work may be presented by an operator, of a table comprising a short main section and an extension section, a finger guard located in front of the mechanism and spaced from the table to permit the work to pass between the guard and the table, means whereby the space between the

guard and the table may be increased by adjusting the guard away from the mechanism, and means whereby the extension is moved into operative position to lengthen 5 the table when the guard is moved away from the mechanism.

5. The combination with mechanism to which pieces of work may be presented by an operator, of a table comprising a main 10 section and an adjustable extension section, a guard located between the operator and the mechanism and spaced above the table to permit the work to pass beneath it, said guard being stationary while in use but adjustable into different positions spaced 15 differently from the table, and means for adjusting the extension section of the table into and out of operative position when the guard is adjusted.

20 6. The combination with mechanism to which pieces of work may be presented by an operator, of a table comprising a main section and an extension section, a guard between which and the table the pieces are 25 presented, said guard being stationary while in use but adjustable over the table from an operative position adjacent to and in front of the mechanism into another position more remote from but still in front of the 30 mechanism, means whereby the distance between the guard and the table is increased as the guard is adjusted to the last-named position and means acting during the adjustment to move the extension section of 35 the table into operative position.

7. The combination with mechanism adapted to operate upon comparatively short, thin pieces of stock and upon longer, thicker pieces, of a table comprising a main 40 section and an extension section, a guard located in front of the mechanism and spaced above the table to form an opening through which the operator presents the pieces to the mechanism, said guard being adjustable over the table toward and from the mechanism, means for controlling the adjustment constructed and arranged to maintain the opening of a size sufficient to prevent the fingers of the operator from pass-

ing through it in all positions of the guard 50 which are within finger length of the mechanism, and a connection between the guard and the extension section of the table for moving the extension section into and out of operative position. 55

8. The combination with mechanism to which pieces of work are presented by an operator, of a table comprising a main section and an extension section, a guard, means whereby the guard may be adjusted into 60 and held in two operative positions, one nearer to both the mechanism and the table and the other farther from both the mechanism and the table, and means for moving the extension into operative position when the guard is moved away from the mechanism and for moving it to inoperative position when the guard is moved toward the mechanism. 65

9. A machine for treating pieces of work 70 having, in combination, mechanism to which the work is presented by an operator, a table, a guard movable into two operative positions, guiding means for the guard extending away from the mechanism, first in 75 a direction substantially parallel to the table and then upwardly, an arm pivoted at one end to the guard, means for controlling the path of movement of the other end of the arm, and a link connecting the arm 80 with a stationary part of the machine.

10. A machine for treating pieces of work having, in combination, mechanism to which the work is presented by an operator, a 85 table, a guard movable into two operative positions, guiding means for the guard extending away from the mechanism, first in a direction substantially parallel to the table and then upwardly, an arm pivoted at one end to the guard, means for controlling 90 the path of movement of the other end of the arm, a link connecting the arm with a stationary part of the machine, and an extension for the table carried by the link.

In testimony whereof I have signed my 95 name to this specification.

DARIUS W. BUNKER.
